MACHINE FOR DIGGING BALLAST

Frank H. Philbrick, Evanston, Ill.

Application November 18, 1935, Serial No. 50,374

22 Claims. (Cl. 37—104)

The invention relates to machines for working or digging ballast from railway road-beds.

The objects of the invention are to provide: a machine of this class which includes a vertically reciprocal gang of digger-tools which are pivoted to swing transversely and means for positively swinging the tools laterally during their digging strokes; a machine in which the diggers, during the ends of their pivotal movement, are cushioned; a machine which includes a guide-frame for the cross-head and cushioning means between the cross-head and the frame operative at the ends of the drop-strokes; a machine in which the cross-head is vertically guided by cushioning means between the cross-head and the frame; a machine for this purpose which includes a guide-frame for the head, which is adapted to bear on the track-rails and is cushioned to reduce the impact resulting from the drop-strokes of the tools and cross-head; a machine which includes pivoted digger-tools and means for retaining some of the tools in extended position during part of the up-strokes of the tools; a machine in which the guide-frame for the cross-head is carried in the truck-frame so it can tilt transversely when the ballast is uneven at the sides of the track; a machine which includes cushioned means for lifting and dropping the head; and other objects which will appear from the detailed description.

The invention consists in the several novel features which are hereinafter set forth and are more particularly defined by claims at the conclusion hereof.

In the drawings:

Fig. 1 is a central longitudinal section of a machine embodying the invention;

Fig. 2 is a plan, the motor being removed, and the guide-frame shown in section;

Fig. 3 is a transverse section on line 3—3 of Fig. 1;

Fig. 4 is a longitudinal section through the drop-head and illustrating the lifting mechanism therefor;

Fig. 5 is a transverse section illustrating the cross-head and the digging tools in raised position;

Fig. 6 is a similar view, illustrating the diggers in lowered position;

Fig. 7 is a side elevation of the drop-head and guide-frame, the frame being shown in section and the drop-head being shown in raised position;

Fig. 8 is a longitudinal section through the

drop-head in lowered position, and the guide-frame;

Fig. 9 is a view, partly in front elevation and partly in section, illustrating the cross-head and the device for sliding one of the tools in its extended position;

Fig. 10 is a section on line 10—10 of Fig. 9;

Fig. 11 is a perspective of the bracket on the cross-head which is engaged by the lifting chain.

The invention is exemplified in connection with a truck adapted to travel on the track-rails equipped with a motor for propelling the truck and for intermittently lifting the digging tools. A suitable truck frame *a* is provided with wheels *b* adapted to run on the rails of the track. An internal combustion motor *c*, with the usual accessories, and a transmission *d*, controlled by a lever *d'*, are mounted on the truck-frame. A longitudinal propeller shaft *e* under the truck-frame is adapted to be driven from the transmission *d* by a pulley *e'*, belts *e''*, and a grooved pulley *e'''* on said shaft. Shaft *e* drives a pinion *f* through reversible gearing *f* to drive a gear *f'* on the axle *b'* of the rear wheels *b* to propel the truck in either direction along the track. Wheels *g*, mounted on longitudinal shafts *g'* under the truck-frame, are provided to transport the truck onto and off the track transversely thereto. Suitable jacks *h* are provided at the front and rear of the truck, having shoes adapted to engage the heads of the rails to lift the truck off the track so that transverse rails may be laid under the wheels *g*. The mechanism thus far described may be of any suitable construction adapted for supporting and transporting the digging mechanism hereinafter set forth.

The picking or digging mechanism comprises a series of tools *l*, *l'*, *l''* and *l'''* adapted to displace the ballast in the cribs between the ties transversely to one side of the track and a similar oppositely acting series of tools *m*, *m'*, *m''*, *m'''* which are adapted to displace the ballast transversely to the other side of the track. These tools are pivoted at their upper ends on pins *20* which are supported in a vertically movable cross-head *t* which is built up of a pair of spaced plates *21* between which the tools are hung. Plates *21* are fixedly secured together in fixed spaced relation by a central block *22* and blocks *23* between the plates. The cross-head is reciprocable vertically so it can be lifted and dropped by mechanism hereinafter described to lift the lower ends of the tools above the ties (Fig. 5) and to lower them into the ballast (Fig. 6). The cross-head is guided and works vertically in a vertical guide-

frame *s*. Heretofore it has been proposed, as exemplified in Patent No. 1,556,605, to depend upon the lowering of the points of the tools into ballast and its resistance to swing the tools transversely of the track for displacing the ballast. The present invention provides for positively swinging the tools transversely during the drop movements of the cross-head to more effectively and efficiently displace the ballast transversely. 5 For this purpose, an upstanding arm *24* rigid with the tool *l* of one series and a similar arm *25* is integrally formed or rigid with the tool *m* of the oppositely acting series. The upper ends of arms *24*, *25* carry rollers *26*, for engaging, respectively, during the reciprocations of the cross-head, a pair of downwardly divergent cams *27* which are carried by the cross-head. The tool *l* is provided with a cam or abutment *28* which is adapted to engage an abutment *29* on the tool *l'*, 10 and similar abutment cams are provided on tools *l²* and *l³* of the series. When the arm *24* engages the cam *27*, with which it is associated, during the drop of the cross-head, the first lever *l* of the series will be positively swung and, through abutments *28*, *29*, the other tools will be positively 15 swung transversely to one side of the track. The oppositely acting set of tools *m*, *m'*, *m²* and *m³* are provided with similar abutments *28*, *29*, so that they will be positively and simultaneously 20 swung in the opposite direction as the arm *25* is lowered. The tools of each set are transversely arranged to progressively move the ballast from the central portion of the track to one side thereof. The upper ends of the tools of one series overlap 25 those of the other and this permits them to be mounted to swing to an effective angle for lateral displacement of the ballast. The tools *l*, *l'* and *l²* and *m*, *m'* and *m²* are adapted to work in the crib between the rails to displace 30 the ballast outwardly under the rails. The tools *l³* and *m³* extend over the rails and to the sides thereof, respectively, for moving the ballast beyond the ends of the ties. During the lift of the 35 cross-head, the weight of the tools which operate between and under the track rails will swing downwardly by gravity under the control of the tools *l* and *m*, which are controlled by the arms *24*, *25* and the cams *27*. In order to retain the outer tools *l³* and *m³* in the extreme outward 40 position in which they swing and prevent the ballast displaced thereby from moving inwardly, devices are provided for retaining said tools in such position until the cross-head has been raised sufficiently for the tools to clear the ballast. Each 45 of these devices (Figs. 9 and 10) comprises a roller *30* journaled in open bearings *31* fixed to one of the plates *21* of the cross-head, and a leaf-spring *32* bearing against the roller to press it into the path of the tool *l³* or *m³*. When the 50 cross-head reaches its lowermost position, the roller *30* will snap under the tool and retain it in its extended position until the cross-head is raised sufficiently to cause the tool to strike the truck-frame at *33*, which will force the tool below the roller *30* and permit the tool to swing into 55 position shown in Fig. 5.

In some instances, it is desirable to vary the transverse displacement of the ballast. For this purpose the cams *27* are pivotally connected at 60 *80* to brackets *81* which are fixed to the bulk-head *48* of the truck. Springs *82* are applied to normally hold the cams *27* into abutting relation with blocks *81*. Cams *27* are provided with downwardly extending arms *83*. A shaft *84* which is 65 mounted in bearings *85* in the lower ends of

brackets *81* is provided with cams *86*, which engage the arms *83* to swing the cams *27* on their pivots *80* to vary the stroke of the arms *24*, *25* which operate the tools as hereinbefore described. Shaft *84* may be adjusted by any suitable means such as an arm *87* and a link *88*. This exemplifies means for varying the positive swinging movement of the tools as it is effected by the cams *27* during the drop-stroke of the cross-head and tools. 10

Spacer-blocks *23* of the cross-head are each provided with a bumper or buffer *34* of rubber, which serves to hold the tools *l³*, *m³*, respectively, to cushion the blows between tools *l³*, *m³* and the cross-head at the end of the drop of the cross-head. Guide-rollers *35* serve to swing the tools *l³*, *m³* transversely and so that the rollers *30* will snap under them. This exemplifies a reciprocable cross-head with pivoted digging tools and means for positively swinging the tools transversely of the track, so they will efficiently and quickly displace the ballast to the opposite sides of the track. 15 20

The cross-head *t* is mounted for vertical movement in guide-frame *s* which is vertically movable in the truck and is adapted to be supported directly by the rails during the lifting strokes of the cross-head. Frame *s* comprises standards *37*, rigidly cross-connected by beams *38* and a plate *39* at their upper ends, and spaced apart 25 to receive the cross-head between them. The standards *37* at either side are connected by brackets *40* (Fig. 8.) Flanged shoes *41*, adapted to engage the track-rails, are carried by brackets *40*. Elastic blocks or buffers *42* are interposed 30 between shoes *41* and brackets *40* to form a cushion between the frame *s* and the rails. These devices constitute cushioned feet between the guide-frame and the rails. Frame *s* is movable vertically so the shoes *41* can be lifted off the 35 rails when the truck is to be propelled any considerable distance along the track. For this purpose, a lifting jack *43*, of the pneumatic or hydraulic type, is mounted on a beam *44* which is fixedly supported on the truck-frame to engage 40 a bracket *45* on the guide-frame *s*. Through the operation of the jack *43*, the frame *s* may be raised and lowered so it will be supported by the truck or directly by the track-rails. 45

Springs *104* are applied between the truck-frame 50 and the brackets *40* at the lower ends of the standards *37* of the frame *s*. These springs are of sufficient force to lift the guide-frame or relieve, in considerable measure, its pressure on the track-rails during the lifting strokes of the cross-head and diggers, at which time their weight is carried by the lifting mechanism for the cross-head hereinafter described. During the lifting strokes of the cross-head and diggers the shoes *41* will be lifted off the rails or the pressure thereon will be relieved by the springs *104* sufficiently 55 to permit the truck to be propelled to bring the digging tools into the different portions of a crib between the ties or between the cribs. These springs make it unnecessary to operate the lifting-jacks *43* to lift the guide-frame *s* off the track during the short movements of the truck necessary to bring the tools into different positions in a crib or between the cribs. 60 65

The end of the drop-stroke of the cross-head 70 and the tools carried thereby is cushioned by shock-absorbing devices between the cross-head and the guide-frame. For this purpose rods *64* have their lower ends pivotally connected at 65 to the cross-head and their upper ends provided 75

with stop or abutment collars 66. Rods 64 pass through wedge-shoes 67, respectively. Each wedge-shoe 67 is held between a pair of wedge-blocks 68 which are slidably guided on a plate 69 which is fixed to the top of the frame s. Springs 70 coiled around rods 71, which extend loosely through the wedge-blocks 68 normally force the blocks together in abutting relation. When the cross-head reaches the end of its drop-stroke the collars 66 will strike the wedges 67, which will force the blocks 68 apart against the force of springs 70 to cushion without recoil the cross-head and the tools carried thereby, the energy being dissipated through friction between the wedges and blocks. These devices also serve to limit the drop of the cross-head in the guide-frame. The shocks imparted to the guide-frame s cause its feet to bear solidly on the track-rails. The shocks thus imparted to said frame are measurably absorbed by the cushion-blocks 42 in the feet of the standards of the guide-frame. A rigid bulk-head 48 and side-plates 49 are rigidly secured to the truck-frame. The guide-frame s is confined against fore and aft movement in an opening in the truck-frame.

Mechanism is provided for alternately lifting and dropping the cross-head which carries the tools, so that the tools will be released for hammer-blows against the ballast. This mechanism comprises a transverse shaft 46, which is journaled in bearings 47 secured on bulkhead 48 and to braces 51. A pair of sprocket-wheels 52, fixed to shaft 46, drive the pair of vertically extending sprocket-chains 53, the forward and vertical reaches of which are parallel and close to the rear of the cross-head t. The lower loops of these chains pass around idler-sprockets 54 which are journaled in levers 55, to which the springs 56 are applied to keep the sprocket-chains taut. Each of the chains 53 carries a pair of laterally projecting lifting rollers 57. Guides 58 are fixed to the cross-head and the guides are spaced so one of the chains 53 can pass between them. Brackets 59 are slidably confined in guides 58. The rollers 57 on the chains 53 are adapted to pass between guides 58 and engage rearwardly projecting lugs on these brackets 59 to lift the cross-head. As the rollers 57 pass around the top of sprockets 52 they will pass rearwardly and away from the brackets to release them so the cross-head, with the tools thereon, will drop. In order to avoid shock resulting from the impact of the lifting mechanism against the cross-head, at the commencement of each upward stroke of the cross-head, brackets 59 are slidably mounted in guides 58 which are fixed to the rear plate 21 of the cross-head. A pair of springs 61 bear against the top of each bracket 59 and each of these springs is coiled around a rod 62, which is fixed in one of the brackets 58. When the rollers 57 strike the brackets 59, the springs will absorb the shock to avoid subjecting the cross-head to excessive impact blows. This exemplifies means for reciprocating the cross-head which carries the tools for drop-hammer blows in which the intermittent impact of the operating mechanism at the commencement of each up-stroke will be cushioned to prevent wear and tear of the parts. Shaft 46 is driven by a sprocket 63 fixed to said shaft, a sprocket-chain 64 and suitable speed reducing mechanism r of the worm-gear type which is driven from the engine driven shaft e through a clutch o under control of a lever p.

In practice it sometimes occurs, for example on curves, that the ballast at one side of the track

is considerably higher than that at the other side, with the result that the tool or tools at the high side will initially receive the entire force of the blow resulting from the drop of the cross-head. This, unless compensated for, would have a tendency to subject the truck to severe impact. To prevent this, the cross-head is free to tilt transversely slightly in the guide-frame s, the rods 64 having sufficient play in the wedges 67 to permit them to swing laterally. The cross-head is guided vertically in the frame s by rubber cushioned blocks 100 which are fixed by means of angle-irons 101 to the cross-head and are provided with metal liners 102 engaged by the standards 37 of the frame which carries the head. These cushion-blocks absorb the shock between the cross-head and said frame resulting from engagement of the diggers at the high side of the ballast. The frame s is held against transverse movement by the depending rail engaging flanges on the shoes 41 and the cushion-blocks 42 between the shoes and brackets 40 at the lower ends of the standards 37 cushion the impact imparted to the frame through the wedges 61. Said frame is free to yield upwardly at either side slightly in the event of unusual height of ballast at one side of the truck. The rubber blocks 42 also cushion the impact of the digger-tools l³, m³, against the rollers 35 during the drop-stroke of the cross-head. During the drop-strokes of the cross-head, the cross-head is entirely disconnected from the lifting chains 53 so that the blows received by it during its drop strokes will not be imparted to its lifting mechanism or to the truck. The frame for carrying the cross-head is cushioned and supported upon the track-rails independently of the truck-frame so that the blows imparted to the frame will not be transmitted to the truck-frame.

When the machine is being transported from place to place, it is necessary to secure the cross-head and tools carried thereby in raised position. For this purpose, a pair of latches 72, which are pivotally held at their upper ends, are provided with hooks 73 at their lower ends to enter slotted plates 74 which are rigid with and project upwardly from the cross-head. A lever 75 fixed to a shaft 76 is connected to conjointly shift the latches 72 through arms 77 fixed to said shafts and spring-pressed rod-connections 78 between the arms and the latches. When the lever 75 is swung downwardly, arms 77, through spring-rods 79, will swing the latches 72 so they will enter the slots in plates 74 at the end of the up-stroke of the cross-head when the cross-head is lifted by its operating mechanism. The pivot-pins for latches 72 are held in elastic blocks 79 in open-ended bearings to yieldingly carry the cross-head from its carrying frame.

The operation will be as follows: During the transporting of the truck, the frame in which the cross-head and tools are mounted will be held in raised position by the jack 43 and the cross-head will be locked in its raised position by latches 72. The truck will be propelled along the track to bring the cross-head and digging-tools over one of the cribs between the ties. The jack 43 will then be operated to lower the guide-frame s so the shoes 40 at the lower ends of the standards 37 will be close to or bear slightly on the rails of the track. The operator will then release the latches 72 so the cross-head and tools can drop. The mechanism for driving shaft 46 will then be started to cause the rollers 57 on chains 53 to intermittently lift the cross-head and release it so it will drop. During the drop

of the cross-head, arms 24 and 25 will engage cams 27 so that all of the tools will be positively swung laterally to effect the displacement of the ballast to the outer sides of the rails. At the end 5 of the down-stroke, the tools l^3, m^3 will be latched in extended position by spring-pressed rollers 30 and retained thereby until the cross-head is lifted sufficiently to disengage said tools from the rollers. The cross-head and tools carried thereby will be 10 arrested at the end of drop-stroke by wedges 67 and spring-pressed wedge-blocks 68 on the guide-frame which then bears on the track-rails. The initial portion of the up-stroke of the cross-head and tools carried thereby will be cushioned by 15 springs 61. The truck will be propelled to move the tools to work different portions of a crib, or between cribs, during the up-strokes of the cross-head.

The invention exemplifies a machine for digging or picking ballast and displacing it to the outer sides of the rails, which is efficient in operation and in which the several mechanisms are cushioned to prevent wear and tear.

The invention is not to be understood as restricted to the details set forth, since these may be modified within the scope of the appended claims, without departing from the spirit and scope of the invention.

Having thus described the invention, what I 30 claim as new and desire to secure by Letters Patent is:

1. In a machine of the class described, the combination of a railway truck, a vertically reciprocable drop head thereon, a series of digger-tools 35 pivotally mounted on the head to swing transversely of the track, power-means for lifting the head with the tools and dropping them to impact the tools against ballast and means for positively swinging the tools during their downward strokes.

40 2. In a machine of the class described, the combination of a railway truck, a vertically reciprocable drop head thereon, a series of digger-tools mounted on the head to move transversely of the track, power-means for lifting the head with the 45 tools and dropping them to impact the tools against ballast and means for positively shifting the tools relatively to one another during their downward strokes.

3. In a machine of the class described, the combination of a railway truck, a vertically reciprocable drop head thereon, a series of digger-tools 50 pivotally mounted on the head to swing in opposite directions transversely of the track, power-means for lifting the head with the tools and dropping them to impact the tools against ballast and means for positively swinging the tools during their downward strokes.

4. In a machine of the class described, the combination of a railway truck, a vertically reciprocable drop head thereon, a series of digger-tools 55 pivotally mounted on the head to swing transversely of the track, power-means for lifting the head with the tools and dropping them to impact the tools against ballast and means for positively swinging the tools during their downward strokes, said means being adjustable to vary the swing of the tools.

5. In a machine of the class described, the combination of a railway truck, a vertically reciprocable head thereon, a series of digger-tools pivotally mounted on the head to swing transversely of the track, means for positively swinging one of the tools during its downward stroke, and means 70 for transmitting pivotal movement from said tool 75 to the other tools.

6. In a machine of the class described, the combination of a railway truck, a vertically reciprocable head thereon, a series of digger-tools pivotally mounted on the head to swing transversely of the track, means for positively swinging one of the tools during its downward stroke, and cams 5 for transmitting pivotal movement from said tool to the other tools.

7. In a machine of the class described, the combination of a railway truck, a vertically reciprocable head thereon, series of digger tools pivotally mounted on the head to swing in opposite directions transversely of the track, means for positively swinging one tool of each series during its 10 downward stroke, and means for transmitting 15 pivotal movement from said tools to the other tools of each series respectively.

8. In a machine of the class described, the combination of a railway truck, a vertically reciprocable head thereon, a series of digger-tools pivotally mounted on the head to swing transversely of the track, including a plurality of tools positioned to dig into the road-bed between the rails and a tool positioned to move over one of the rails, and means for positively swinging all of said tools 20 during their down-strokes.

9. In a machine of the class described, the combination of a railway truck, a vertically reciprocable head thereon, a series of digger tools pivotally mounted on the head to swing transversely 30 of the track, including a plurality of tools positioned to dig into the road-bed between the rails and a tool positioned to move over one of the rails, cam-means for positively swinging one of said tools during its down-stroke, and cams between 35 the tools for swinging the other tools.

40 10. In a machine of the class described, the combination of a railway truck, a vertically reciprocable head thereon, a series of digger-tools pivotally mounted on the head to swing transversely of the track, means for lifting and dropping the head, means for swinging the tools during 45 their down-strokes, and cushion-means for limiting the swing of the tools.

11. In a machine of the class described, the combination of a railway truck, a vertically reciprocable drop head thereon, a series of digger-tools pivotally mounted on the head to swing transversely of the track, power-means for lifting the head with the tools and dropping them 50 to impact the tools against ballast, means for swinging one of the tools during its downward stroke, and means for retaining said tool in its shifted position during a portion of the upstroke thereof.

55 12. In a machine of the class described, the combination of a railway truck, a vertically reciprocable drop head thereon, series of digger-tools pivotally mounted on the head to swing in opposite directions transversely of the track, power-means for lifting the head with the tools and dropping them to impact the tools against ballast, means for swinging the tools during their 60 downward strokes, and means for retaining one tool of each series in its shifted position during a portion of the upstroke thereof.

65 13. In a machine of the class described, the combination of a wheeled railway truck, a vertical guide-frame carried by and movable vertically in the truck and provided with means for bearing on the track-rails, a head vertically reciprocable in the frame, a series of digger-tools mounted on the cross-head, means carried by the truck for lifting and dropping the head, and cushioning-means between the head and the 70 75

frame operative at the ends of the drop-strokes of the head.

14. In a machine of the class described, the combination of a wheeled railway truck, a vertically reciprocable guide-frame carried by the truck and provided with means for bearing on the track-rails, a vertically reciprocable head mounted in the guide-frame, a series of digger-tools on the head, means carried by the truck for lifting and dropping the head, and means between the frame and the head for arresting the drop of the head, comprising a wedge and spring-pressed blocks shiftable by the wedge.

15. In a machine of the class described, the combination of a wheeled railway truck, a vertically extending guide-frame carried by and movable vertically in the truck and provided with feet for bearing on the track-rails, a head vertically reciprocable in the frame, a series of digger-tools mounted on the cross-head, means carried by the truck for lifting and dropping the head, and means for cushioning the frame on the rails.

16. In a machine of the class described, the combination of a wheeled railway truck, a vertically extending guide-frame carried by and movable vertically in the truck and provided with feet for bearing on the track-rails, a head vertically reciprocable in the frame, a series of digger-tools mounted on the cross-head, means carried by the truck for lifting and dropping the head, cushioning-means between the head and the frame operative at the ends of the drop-strokes of the head, and means for cushioning the frame on the rails.

17. In a machine of the class described, the combination of a wheeled railway truck, a vertically reciprocable guide-frame carried by the truck and provided with feet for bearing on the track-rails, a vertically reciprocable head mounted in the guide-frame, a series of pivoted digger-tools on the head, means on the truck for lifting and dropping the head, and cushioned vertical guide-means between the head and the frame to permit transverse tilting of the cross-head in the frame.

18. In a machine of the class described, the combination of a wheeled railway truck, a vertically reciprocable guide-frame carried by and transversely tiltable in the truck and provided with feet for bearing on the track-rails, a vertically reciprocable head mounted in the guide-frame, digger-tools on the head, means carried by the truck for lifting and dropping the head, cushioned vertical guide-means between the head and the guide-frame, and cushioning-means between the frame and the track-rails.

19. In a machine of the class described, the combination of a wheeled railway truck, a vertically reciprocable guide-frame carried by the truck provided with feet for bearing on the track-rails, a vertically reciprocable head mounted in the guide-frame, a series of digger-tools on the head, means carried by the truck for lifting and dropping the head, spring-means applied to relieve the pressure of the guide-frame on the rails while the head is being lifted and supported by the lifting mechanism, and means between the head and the frame for arresting the head at the end of a drop-stroke, whereby the frame will be forced downwardly on the rails at the end of the drop-stroke.

20. In a machine of the class described, the combination of a wheeled railway truck, a vertically reciprocable guide-frame carried by the truck provided with feet for bearing on the track-rails, a vertically reciprocable head mounted in the guide-frame, a series of digger-tools on the head, means carried by the truck for lifting and dropping the head, spring-means applied to relieve the pressure of the guide-frame on the rails while the head is being lifted and supported by the lifting mechanism, and cushioned means between the head and the frame for arresting the head at the end of a drop stroke, whereby the frame will be forced downwardly on the rails at the end of the drop-stroke.

21. In a machine of the class described, the combination of a wheeled railway truck, a vertically reciprocable guide-frame carried by the truck and provided with feet for bearing on the track-rails, a vertically reciprocable head mounted in the guide-frame, a series of digger-tools on the head, means carried by the truck for lifting and dropping the head, means for lifting the guide-frame upwardly to disengage it from the rails, and latch means between the frame and the cross-head for locking the latter in its raised position.

22. In a machine of the class described, the combination of a wheeled railway truck, a vertically reciprocable guide-frame carried by the truck and provided with feet for bearing on the track-rails, a vertically reciprocable head mounted in the guide-frame, a series of digger-tools on the head, means carried by the truck for lifting and dropping the head, means for lifting the guide-frame upwardly to disengage it from the rails, and cushioned latch-means between the frame and the cross-head for locking the latter in its raised position.
